UNITED STATES PATENT OFFICE.

FRANK E. HERDMAN, OF WINNETKA, ILLINOIS.

DEVICE FOR REGULATING CURRENT ADMITTED TO ELECTRIC MOTORS.

SPECIFICATION forming part of Letters Patent No. 548,829, dated October 29, 1895.

Application filed March 22, 1895. Serial No. 542,752. (No model.)

To all whom it may concern:

Be it known that I, FRANK E. HERDMAN, a citizen of the United States, residing at Winnetka, county of Cook, and State of Illinois, 5 have invented a new and useful Improvement in Devices for Regulating Current Admitted to Electric Motors, of which the following is a full, clear, and exact description, reference being had to the accompanying drawings, which 10 form a part of this specification.

In the use of electric motors supplied from a power-station it often occurs that the power-station places restrictions that will not permit beyond a certain number of ampères to be 15 initially admitted at the first closing of the switch, and additional ampères have to be taken gradually. Thus if the initial amount be ten ampères and the motor requires fifty ampères to do its full work it is necessary to 20 provide means to allow the increase to occur gradually. If a device such as is shown in Letters Patent No. 530,773, issued to me December 11, 1894, in which a solenoid in the circuit to the armature is used to control the 25 speed with which the resistance is cut out, should be used alone, the solenoid would have to act at ten ampères, and any current admitted beyond that would have to be admitted so gradually as to make it objectionable, for 30 in the device of that patent the retarding effect produced by the solenoid when energized remains, and the remainder of the movement of admission of current above the amount for which it is adjusted would have to be against 35 this set retarding effect. While, broadly considered, this would prevent the admission of current beyond the initial ampérage, except in a gradual manner, still it would cause such a sluggish movement of the motor under a 40 light load as to be very objectionable. This is especially objectionable where the motor is used in connection with an elevator, which has at times a heavy load and at other times a light load. When the load is light, the motor should 45 have the capacity to get under way as rapidly as possible. Of course when heavily loaded it is not expected to get under way rapidly. If the device of Patent No. 530,773 be used alone and without modification and the solenoid is 50 adjusted for a given current—say ten ampères—then any load requiring a greater current would cause a certain retarding effect and make the admission of the current proper for

such load; but with a light load, which would require only ten ampères, the same action 55 would take place and, being unnecessary, is objectionable in that it retards the time in which under those conditions the motor gets under way.

The device forming the subject of this invention while the same in principle and containing the broad invention described and claimed in Patent No. 530,773, still has certain additions and modifications which especially adapt it to overcome the above defects and is 65 applicable for the purpose enumerated. In general its construction and operation permit the initial amount of current—ten ampères, or whatever the required amount may be—to be admitted on the first closing of the 70 switch, and then permit predetermined increments beyond this to be admitted successively and gradually to meet the requirements of the power-station. If, for instance, the load would require fifty ampères to start it, 75 then this device would admit it gradually until the fifty ampères are admitted, the graduation being governed by that which is permitted by the power-station; but as soon as this maximum current is reached then the further 80 admission would be prevented; but the resistance in the armature-circuit would be cut out as rapidly as possible without causing further increase. If there were a light load on the motor—where, for instance, only ten or 85 twenty ampères were required to start it—the operation would be the same as before until the ten or twenty ampères were admitted, when the resistances would be cut out of circuit as rapidly as possible without causing the increase of current to be more rapid than the requirements of the power-station, the point 90 in this case being that the device regulates the admission of the amount of current to the motor sufficient to start it, so that it shall be admitted only in the time predetermined for its 95 admission. The device for accomplishing this is shown in the accompanying drawings, in which—

Figure 1 is a front view of the device attached to a motor. Fig. 2 is a diagram showing the wiring. Fig. 3 is a side elevation of the device. Fig. 4 is a section on line *x x* of Fig. 3. Fig. 5 is a section on line *w w* of Fig. 4. Fig. 6 is a plan view of a modified form. 100 Fig. 7 is a section on line *y y* of Fig. 6.

A is an electric motor; B, its armature; C, the field-magnet, the wires from the source of current-supply passing directly to the fields.

D is the armature-controlling switch, and is of the type described in Letters Patent No. 519,120, and d is the shaft for operating said switch.

d' d² are the brushes by which the current from the two poles of current-supply passes to the switch D, and from the brushes d³ d³ the current is led to the solenoid E, the core e of which is connected to resistance-arm F, having the brush f.

g is a plate in electrical connection with the resistances and with brush d⁴.

The arm F is in electrical connection with the armature through solenoid I, and the armature is in electrical connection with the other pole of current-supply by wire connecting with brush d⁵ of switch D.

Speaking generally, when the switch is operated the current is admitted to solenoid E, energizing it and causing the arm to travel over the resistances, admitting current to armature through resistances, which are gradually cut out until the arm or brush f reaches the plate g, when the full force of the current passes to the armature.

Speaking now of Figs. 3, 4, and 5, H is a dash-pot connected to the lower end of the core of solenoid E by means of the side bars h. H' is piston of this dash-pot, and is connected by the means of its piston-rod h' with the frame holding the solenoid E. In the piston-rod of the dash-pot H is placed a valve h², the valve-stem h³ of which is connected to one end of the centrally-fulcrumed rocker J, the other end of the rocker being attached to the core of solenoid I. K is a spring, which is set to act against or resist the movement of the core of solenoid I. This spring is so adjusted that the distance the core of solenoid I is drawn upward is directly proportional to the amount of current passing to the armature. Thus if the solenoid I is adjusted for ten (10) ampères, then when it is excited by ten ampères the spring would be compressed a certain fixed amount, and each additional ten ampères of current passing through the solenoid I will cause the spring to be compressed an additional and like amount. The piston H' of the dash-pot H has within it the secondary piston H², provided with an opening h⁴ through it, regulated by the screw h⁵. This piston has a sleeve h⁶, surrounding the piston-rod h'. In the piston-rod h' of dash-pot H is a slot formed between the points k k, and in the sleeve h⁶ is a slot between the points k' k'. A pin L, connected to the valve-stem h³, works in this slot. Normally the pin L rests at the top of the slot and holds the secondary piston H². The piston-rod h' is hollow, and in the piston-rod are a number of ports 1 2 3 4 5 above the piston, the port 1 being open and the ports 2 3 4 5 being closed by the secondary piston H² at the beginning of the operation. When the switch is operated, the solenoid E is energized

and commences to move the arm over the resistances, the speed being determined by the speed with which the liquid will pass from one side of piston H' to the other through port 1. As soon as the solenoid I becomes excited sufficiently to move the core a distance sufficient to compress the spring through the medium of the rocker J, the valve-stem h³ will be acted on, and moved downward, so that valve h² will close the port 1. When this has occurred, the further movement of solenoid E and the resistance-arm is prevented; but as this movement has also released the pin from holding the secondary piston H² it falls, the speed of its fall being determined by the extent of outlet formed by the adjustment of the screw h⁵. As soon as the secondary piston H² has fallen sufficiently to uncover port No. 2, the solenoid E again commences to act, and acts until the solenoid I has received a second increment of current sufficient to compress the spring K enough to again force downward, through the medium of the rocker, the valve-stem h³ and valve h², so as to cover port No. 2, at which time the sleeve of the secondary piston H² is relieved from the pin, with which it again came in contact at the end of its previous downward movement. The length of the slot between the points k k being sufficient to allow the piston H² to move sufficiently to open the port, it again moves downward until it opens port No. 3, at which time the solenoid again acts. This is continued until the necessary ampèreage is admitted.

In order to prevent the motor receiving too much current—thus, for instance, if fifty ampères is the limit which it is desired to pass to the motor—then the arrangement is such that the valve covers the lowest port when the solenoid I has been energized sufficiently to compress the spring an amount equal to fifty ampères, and as the secondary piston H² in the downward movement has no other ports to uncover there can be no further movement of the solenoid E. By this construction it will be seen that by means of the solenoid I, the rocker J, the spring K, and the valve h² the machine initially is only allowed to receive a certain increment of current, and by means of the adjustment of the screw h⁵ in the secondary piston H² the time may be determined which shall be allowed before the machine receives any additional increment of current, and can be adjusted exactly to the time required for an additional increment in the current passing, and for each succeeding increment the same operation takes place. In consequence, if a machine requires, say, fifty ampères to get under way the admission of current at the first closing of the switch cannot exceed ten ampères. Then the time at which the fifty ampères would be admitted to the machine would be regulated by the passing of this secondary piston over the successive ports, the solenoid I being energized proportionately by each increment of current until it compresses the spring K a suitable amount.

Thus the speed with which the rheostat-arm passes over the contacts is not set for any amount of resistance, but simply according to the increment of current—that is, if ten ampères is admitted to the motor and the motor is so slow in getting under way that the rheostat-arm would only move, say, two or three contacts before the current would be increased to the amount of the increment then the action of this device would be such as to prevent its going farther until the secondary piston had opened another port. If the next increment will permit the motor to get under way and develop a counter electromotive force, so that a greater amount of resistance could at this time be cut out, then that amount can be cut out, as the distance which the rheostat-arm passes is only controlled by the amount of current passing to the armature. Thus if ten ampères would start the machine and develop its counter electromotive force then as soon as the solenoid I has checked the dash-pot long enough for these ten ampères to perform their work it would permit the rheostat-arm to pass over the resistances as quickly as the mechanism could carry it.

In Figs. 6 and 7 I have shown a modified form, in which, as before, E is the solenoid controlling and operating the resistance-arm F. H is a dash-pot connected to the core of the solenoid, and h' is a piston, the rod of which is connected to the frame carrying the solenoid, there being an opening from one side to the other of the piston. h^3 is a valve-stem connected to the rocker J, and between the connection of the valve-stem to the rocker J and the frame is a spring j. This rocker J instead of having, as in the other case, a fixed fulcrum is pivotally connected at its center to the valve-stem h^3 and at one end to the core of the supplemental solenoid I, and K is a spring against which the core of the supplemental solenoid I works, as in the former case, the other end of the rocker being connected to the piston-rod h^6 of a piston M^2 in a secondary dash-pot M. M' is a pin adjustable in a stand, and is in alignment with the rocker J in its movement. The operation of this modification is as follows: When the solenoid I is energized sufficient to compress the spring K an equivalent to the increment of current desired to be admitted, it forces down the valve-stem h^3 , compressing the spring j and closing the port in the piston H' of the dash-pot H. This is accomplished with the rocker acting as fulcrum upon its connection with the end of the piston-rod h^6 of the supplemental dash-pot M. As soon as this is down the spring j commences to act and acts upon the rocker, so that it swivels on its connection with the core of the solenoid I and lifts the piston-rod and piston of the supplemental dash-pot M. The speed with which said piston is lifted is determined by the adjustment of the screw h^5 , controlling the orifice between one side and the other of the piston H^2 in the supplemental dash-pot

M. This upward movement of the spring forces up the valve-stem h^2 , again opening the port of the piston in the main dash-pot 70 H, and the solenoid I again acts to move the rheostat-arm.

In order to prevent too great an amount of current being admitted by the adjustment of the screw M', a further movement of the piston of the supplemental dash-pot M may be prevented after the rocker in its previous movement has reached contact with the screw.

Having now fully described my invention, what I claim, and desire to protect by Letters Patent, is—

1. The combination with a translating device, electric connections from a source of current supply to said translating device, resistances in the said circuit to the translating device, an arm for controlling said resistances, of a device adapted to retard the movement of said arm over said resistances, mechanism connected with said retarding device adapted when operated to render said retarding device capable of preventing the movement of said arm, and a solenoid in the circuit to the translating device, operatively connected with said mechanism, the arrangement and connection being such that when the solenoid receives a predetermined increment of current the mechanism is operated.

2. The combination with a translating device, electric connections from a source of current supply to a translating device, resistances in the said circuit to the translating device, an arm for controlling said resistances, of a device adapted to retard the movement of said arm over said resistances, mechanism connected with said retarding device adapted when operated to render said retarding device capable of preventing the movement of said arm, and a solenoid in the circuit to the translating device, operatively connected with said mechanism, the arrangement and connection being such that when the solenoid receives a predetermined increment of current the mechanism is operated, a supplemental device adapted to be brought into action when said mechanism is operated and return the retarding device to its normal mechanical resistance.

3. The combination with a translating device, electric connections from a source of current supply to said translating device, resistances in the said circuit to the translating device, an arm for controlling said resistances, of a device adapted to retard the movement of said arm over said resistances, mechanism connected with said retarding device adapted when operated to render said retarding device capable of preventing the movement of said arm, and a solenoid in the circuit to the translating device, and operatively connected with said mechanism, the arrangement and connection being such that when the solenoid receives a predetermined increment of current, the mechanism is operated, a supplemental device adapted to be brought into ac-

tion when the mechanism is operated and return the retarding device to its normal mechanical resistance, the construction of said supplemental device being such that it acts to return said retarding device to its normal resistance in a predetermined time.

4. The combination with a translating device, electric connections from a source of current supply to said translating device, resistances in the said circuit to the translating device, an arm for controlling said resistances, of a device adapted to retard the movement of said arm over said resistances, mechanism connected with said retarding device adapted when operated to render said retarding device capable of preventing the movement of said arm, a solenoid in the circuit to the translating device, and operatively connected with said mechanism, the arrangement and connection being such that when the solenoid receives a predetermined increment of current the mechanism is operated, a supplemental device adapted to be brought into action when the mechanism is operated and return the retarding device to its normal mechanical resistance, the construction of said supplemental device being such that the time in which it acts to return said retarding device to its normal resistance may be varied by previous adjustment.

5. The combination with a translating device, electric connections from a source of current supply to said translating device, resistances in said circuit to the translating device, of an arm for controlling said resistances, a device adapted to retard the movement of said arm over said resistances, mechanism connected with said retarding device adapted when operated to render said retarding device capable of preventing the movement of said arm, a solenoid in the circuit to the translating device, and operatively connected with said mechanism, the arrangement and connection being such that when the solenoid receives the predetermined increments of current its core is moved a fixed amount, and the retarding device is rendered capable of preventing the further movement of said arm, a supplemental device adapted to be brought into action at each time the retarding device is so acted on, and return the retarding device to its normal resistance.

6. In combination with a translating device, electric connections from a source of current supply to said translating device, resistances in the circuit to the translating device, an arm for controlling said resistances, a solenoid to operate said arm and electrical connections to said solenoid, a dash pot for controlling the movement of said solenoid, an opening between the two sides of the piston in the said dash pot, a valve for closing said opening, a valve stem, a secondary solenoid in series with the translating device, connection between the core of the second solenoid and the valve stem of the valve of the dash pot of the first solenoid, a mechanical re-

sistance device acting against the movement of the core of the second solenoid, said mechanical resistance device being regulated so that when a predetermined increment of current is admitted to the translating device, said core is operated so as to move the valve to close the opening in the piston of the dash pot of the first solenoid.

7. In combination with a translating device, electrical connections from a source of current supply to said translating device, resistances in the circuit to the translating device, an arm for controlling said resistances, a solenoid to operate said arm and electric connections to said solenoid, a dash pot for controlling the movement of said solenoid, two openings between the sides of the piston in said dash pot, valve for closing said openings, a valve stem, a secondary solenoid in series with the translating device, connection between the core of the second solenoid and the valve stem of the valve of the dash pot of the first solenoid, a mechanical resistance device acting against the movement of the core of the second solenoid, said mechanical resistance device being regulated so that when a predetermined increment of current is admitted to the translating device, said core is operated so as to operate said valve stem to close the opening in the piston of the dash pot of the first solenoid, a supplemental piston, having an orifice, sustained by the valve stem and in the initial operation adapted to close the lower of the two ports, and to be released from the valve stem when the valve stem is operated by the secondary solenoid, and move downward and uncover the lower port.

8. In combination with a translating device, electrical connections from a source of current supply to said translating device, resistances in the circuit to the translating device, an arm for controlling said resistances, a solenoid to operate said arm and electrical connections to said solenoid, a dash pot for controlling the movement of said solenoid, two openings between the sides of the piston in said dash pot, valve for closing said openings, a valve stem, a secondary solenoid in series with the translating device, connection between the core of the second solenoid and the valve stem of the valve of the dash pot of the first solenoid, a mechanical resistance device acting against the movement of the core of the second solenoid, said mechanical resistance device being regulated so that when a predetermined increment of current is admitted to the translating device said core is operated so as to operate the valve stem to close the opening in the piston of the dash pot, of the first solenoid, a supplemental piston, having an orifice, sustained by the valve stem and in the initial operation adapted to close the lower of the two ports, and to be released from the valve stem when the valve stem is operated by the secondary solenoid, and move downward and uncover the lower port, a regulat-

ing screw in said orifice in the supplemental piston.

9. In combination with a translating device, electrical connections from a source of current supply to said translating device, resistances in the circuit to the translating device, an arm for controlling said resistances, a solenoid to operate said arm and electrical connections to said solenoid, a dash pot for controlling the movement of said solenoid, a series of ports one below the other forming connections from one side to the other of the piston in said dash pot, a valve adapted in its movement to successively close said ports, a valve stem, a secondary solenoid in series with the translating device, connection between the core of the secondary solenoid and the valve stem of the dash pot of the first solenoid, a mechanical resistance device acting against the movement of the core of the second solenoid, said mechanical resistance device being regulated so that with the admission of successive predetermined increments of current to the translating device, the core is operated so as to operate the valve stem to cause the valve to close successively the ports in the piston of the first solenoid dash pot.

10. In combination with a translating device, electrical connections from a source of current supply to said translating device, resistances in the circuit to the translating device, an arm for controlling said resistances, a solenoid to operate said arm and electrical connection to said solenoid, a dash pot for controlling the movement of said solenoid, a series of ports one below the other forming connections from one side to the other of the piston in said dash pot, a valve adapted in its movement to successively close said ports, a valve stem, a secondary solenoid in series with the translating device, connection between the core of the second solenoid and the valve stem, of the dash pot of the first solenoid, a mechanical resistance device acting against the movement of the core of the second solenoid, said mechanical resistance device being regulated so that with the admission of successive predetermined increments of current to the translating device, the core is operated so as to cause the valve stem to operate the valve to close successively the ports in the piston of the first solenoid dash pot, a supplemental piston, having an orifice, sustained by the valve stem and, in the initial operation, adapted to close all but the upper port and successively to be released in the successive movement of the valve stem and move downward a distance to uncover a port next below the port closed in the successive movement of the valve stem.

11. In combination with a translating device, electrical connections from a source of current supply to said translating device, resistances in the circuit to the translating device, an arm for controlling said resistances, a solenoid to operate said arm and electrical connection to said solenoid, a dash pot for con-

trolling the movement of said solenoid, a series of ports one below the other forming a connection from one side to the other of the piston in said dash pot, a valve adapted in its movement to successively close said ports, a valve stem, a secondary solenoid in series with the translating device, connection between the core of the secondary solenoid and the valve stem of the dash pot of the first solenoid, a mechanical resistance device acting against the movement of the core of the second solenoid, said mechanical resistance device being regulated so that with the admission of successive predetermined increments of current to the translating device, the core is operated so as to cause the valve stem to operate the valve to close successively the ports in the piston of the first solenoid dash pot, a supplemental piston, having an orifice, sustained by the valve stem, and in the initial operation adapted to close all but the upper port and successively to be released in the successive movements of the valve stem, and move downward a distance to uncover a port next below the port closed in the successive movements of the valve stem, the arrangement being such that when the desired limit of increment of current has been reached the supplemental piston is below the lowest port in the dash pot piston.

12. In combination with a translating device, electrical connections from a source of current supply to said translating device, resistances in the circuit to the translating device, an arm for controlling said resistances, a solenoid to operate said arm and electrical connections to said solenoid, a dash pot for controlling the movement of said solenoid, a series of ports one below the other forming connections from one side to the other of the piston in said dash pot, a valve adapted in its movement to successively close said ports, a valve stem, a secondary solenoid in series with the translating device, connection between the core of the secondary solenoid and the valve stem, a mechanical resistance device acting against the movement of the core of the second solenoid, said mechanical resistance device being regulated so that with the admission of successive predetermined increments of current to the translating device, the core is operated so as to cause the valve stem to operate the valve to close successively the ports in the piston of the first solenoid dash pot, a supplemental piston, having an orifice, sustained by the valve stem, and, in the initial operation, adapted to close all but the upper port, a slot in the piston rod of first mentioned piston, a slot in the said piston rod of the supplemental piston, a pin connected to the valve stem and projecting within the slot in the supplemental piston and adapted to sustain the supplemental piston when the valve stem is at rest, but when the valve stem moves the supplemental piston is released.

13. In combination with a translating device, electrical connections from a source of

current supply to said translating device, resistances in the circuit to the translating device, an arm for controlling said resistances, a solenoid to operate said arm and electrical connections to said solenoid, a dash pot for controlling the movement of said solenoid, a series of ports one below the other forming connections from one side to the other of the piston in said dash pot, a valve adapted in its movement to successively close said ports, a valve stem, a secondary solenoid in series with the translating device, connection between the core of the second solenoid and the valve stem of the dash pot of the first solenoid, a mechanical resistance device acting against the movement of the core of the second solenoid, said mechanical resistance device being regulated so that with the admission of successive predetermined increments of current to the translating device, the core is operated so as to cause the valve stem to operate the valve to close successively the ports in the piston of the first solenoid dash pot, a supplemental piston, having an adjustable orifice, sustained by the valve stem and in the initial operation adapted to close all but the upper port, a slot in the piston rod of first mentioned piston, a slot in the piston rod of the supplemental piston, a pin connected to the valve stem and projecting within the slot in the supplemental piston and adapted to sustain the supplemental piston when the valve stem is at rest, but when the valve stem moves the supplemental piston is released.

14. In combination with a translating device, electrical connections from a source of current supply to said translating device, resistances in the circuit to the translating device, an arm for controlling said resistances, a solenoid to operate said arm, and electrical connections to said solenoid, a dash pot for controlling the movement of said solenoid, an opening between the two sides of the piston in said dash pot, a valve for closing said opening, a valve stem, a secondary solenoid in series with the translating device, connection between the core of the second solenoid and the said valve stem, a spring acting against the movement of the core of second solenoid, said spring being regulated so that when a predetermined increment of current is admitted to the translating device, said core is operated so as to cause the valve stem to operate the valve to close the opening in the piston of the dash pot of the first solenoid.

15. In combination with a translating device, electrical connections from a source of current supply to said translating device, resistances in the circuit to the translating device, an arm for controlling said resistances, a solenoid to operate said arm and electrical connection to said solenoid, a dash pot for controlling the movement to said solenoid, two openings between the sides of the piston in said dash pot, valves for closing said openings, a valve stem, a secondary solenoid in se-

ries with the translating device, connection between the core of the second solenoid and the valve stem, a spring acting against the movement of the core of the second solenoid, said spring being regulated so that when a predetermined increment of current is admitted to the translating device said core is operated so as to cause the valve stem to operate the valve to close the opening in the piston of the dash pot of the first solenoid, a supplemental piston, having an orifice, sustained by the valve stem and in the initial operation adapted to close the lower of the two ports, and to be released from the valve stem when the valve stem is operated by the secondary solenoid, and move downward and uncover the lower port.

16. In combination with a translating device, electrical connections from the source of current supply to said translating device, resistances in the circuit to the translating device, an arm for controlling said resistances, a solenoid to operate said arm and electrical connections to said solenoid, a dash pot for controlling the movement of said solenoid, two openings between the sides of the piston in said dash pot, valves for closing said openings, a valve stem, a secondary solenoid in series with the translating device, connection between the core of the second solenoid and the valve stem, a spring acting against the movement of the core of the second solenoid, said spring being regulated so that when a predetermined increment of current is admitted to the translating device said core is operated so as to cause the valve stem to operate the valve to close the opening in the piston of the dash pot of the first solenoid, a supplemental piston, having an orifice, sustained by the valve stem and in the initial operation adapted to close the lower of the two ports, and to be released from the valve stem when the valve stem is operated by the secondary solenoid, and move downward and uncover the lower port.

17. In combination with a translating device, electrical connections from the source of current supply to said translating device, resistances in the circuit to the translating device, an arm for controlling said resistances, a solenoid to operate said arm and electrical connections to said solenoid, a dash pot for controlling the movement of said solenoid, a series of ports one below the other forming connections from one side to the other of the piston in said dash pot, a valve adapted in its movement to successively close said ports, a valve stem, a secondary solenoid in series with the translating device, connection between the core of the second solenoid and the valve stem, a spring acting against the movement of the core of second solenoid, said spring being regulated so that with the admission of successive predetermined increments of current to the translating device the core is operated so as to close successively the

ports in the piston of the first solenoid dash pot.

18. In combination with a translating device, electrical connections from the source of current supply to said translating device, resistances in the circuit to the translating device, an arm for controlling said resistances, a solenoid to operate said arm and electrical connections to said solenoid, a dash pot for controlling the movement of said solenoid, a series of ports one below the other, forming a connection from one side to the other of the piston in said dash pot, a valve adapted in its movement to successively close said ports, a valve stem, a secondary solenoid in series with the translating device, connection between the core of the second solenoid and the valve stem, of the dash pot, of the first solenoid, a spring acting against the movement of the core of second solenoid, said spring being regulated so that with the admission of successive predetermined increments of current to the translating device, the core is operated so as to cause the valve stem to operate the valve to close successively the ports in the piston of the first solenoid dash pot, a supplemental piston, having an orifice, sustained by the valve stem and in the initial operation adapted to close all but the upper port and successively to be released, in the successive movements of the valve stem, and move downward a distance to uncover a port next below the port closed in the successive movements of the valve stem.

35. 19. In combination with a translating device, electrical connections from the source of current supply to said translating device, resistances in the circuit to the translating device, an arm for controlling said resistances, a solenoid to operate said arm and electrical connections to said solenoid, a dash pot for controlling the movement of said solenoid, a series of ports one below the other forming a connection from one side to the other of the piston in said dash pot, a valve adapted in its movement to successively close said ports, a valve stem, a secondary solenoid in series with the translating device, connection between the core of the second solenoid and the valve stem, a spring acting against the movement of the core of the second solenoid, said spring being regulated so that with the admission of successive predetermined increments of current to the translating device, the core is operated so as to cause the valve stem to operate the valve to close successively the ports in the piston of the first solenoid dash

pot, a supplemental piston having an orifice sustained by the valve stem, and in the initial operation adapted to close all but the upper port and successively to be released, in the successive movements of the valve stem, and move downward a distance to uncover the port next below the port closed in the successive movements of the valve stem, the arrangement being such that when the desired limit of increments of current has been reached the supplemental piston is below the lowest port in the dash pot cylinder.

20. The combination with a translating device, electric connections from a source of current supply to said translating device, a device for admitting the current to said translating device, mechanism adapted to control the operation of said current admitting device, said controlling device being so adjusted that when the translating device receives a predetermined increment of current said current admitting device is held from further acting.

21. The combination with a translating device, electric connections from a source of current supply to said translating device, a device for admitting the current to said translating device, mechanism adapted to control the operation of said current admitting device, said controlling device being so adjusted that when the translating device receives a predetermined increment of current said current admitting device is held from further acting, and means to automatically release said controlling device.

22. The combination with a translating device, electric connections from a source of current supply to said translating device, a device for admitting the current to said translating device, mechanism adapted to control the operation of said current admitting device, said controlling device being so adjusted that when the translating device receives a predetermined increment of current said current admitting device is held from acting, the operation being such that with successive predetermined increments of current, said current admitting device is held from acting and intermediate thereto is released from the control of said controlling device.

In testimony of which invention I have hereunto set my hand.

FRANK E. HERDMAN.
